UNITED STATES PATENT OFFICE.

LEANDRO STEEL, OF PROVO, UTAH.

DESIGN FOR AN IRRIGATING-TOOL.

SPECIFICATION forming part of Design No. 27,173, dated June 8, 1897.

Application filed April 22, 1897. Serial No. 633,403. Term of patent 14 years.

To all whom it may concern:

Be it known that I, LEANDRO STEEL, residing at Provo, in the county of Utah and State of Utah, have invented and produced a new 5 and original Design for an Irrigating-Tool, of which the following is a specification, reference being had to the accompanying drawings, in which—

Figure 1 is a perspective view of my design, and Fig. 2 is a side elevation of the same.

The leading feature of my design consists in the ornamental representation of a central or handle-like member A and the spade-like portion C at one end and the hoe member G 15 at the opposite end, the palm of the spade projecting at right angles to the cutting edge of the hoe. The spade representation C con-

ncts with the handle A by a ferrule-like member B, which has a curved portion b which connects with the shovel C. The hoe has an 20 upwardly-extending portion F, which joins with an arch member E, which projects above the handle A, as shown in Fig. 2, and which terminates in a downwardly-extending ferrule portion D, which connects with the handle. 25

What I claim is—

The design for an irrigating-tool, substantially as shown and described.

In testimony whereof I affix my signature in presence of two witnesses.

LEANDRO STEEL.
